UNITED STATES PATENT OFFICE.

WILLIAM E. JAQUES, OF GRAND RAPIDS, MICHIGAN, ASSIGNOR TO ALFRED O. CROZIER, OF GRAND RAPIDS, MICHIGAN.

MACHINE FOR MAKING PRODUCTS OF CEMENT OR ARTIFICIAL STONE.

SPECIFICATION forming part of Letters Patent No. 738,910, dated September 15, 1903.

Application filed June 30, 1902. Serial No. 113,773. (No model.)

To all whom it may concern:

Be it known that I, WILLIAM E. JAQUES, a citizen of the United States of America, residing at Grand Rapids, in the county of Kent and State of Michigan, have invented certain new and useful Improvements in Machines for Making Products of Cement or Artificial Stone; and I hereby declare the following to be a full, clear, and exact description of the invention, such as will enable others skilled in the art to which it pertains to make and use the same.

This invention relates to improvements in machines for making bricks or blocks or products of cement or artificial stone.

The primary object of this invention is to provide a machine wherein plastic material having Portland or hydraulic cement as an ingredient is operated upon within a die or mold having a removable bottom wherein the laden bottom is removed from the chamber of the mold and replaced by an unladen mold-bottom and wherein the brick or product removed from the chamber of the mold upon a mold-bottom is not directly touched or handled independently of the said bottom until the material which composes the product has set enough to render the product capable of being directly handled without liability of mutilating or injuring the product.

Another object of this invention is to provide a machine or apparatus of the character indicated which is simple in construction and reliable, convenient, and efficient in its operation.

With these objects in view and to the end of realizing other advantages hereinafter appearing the invention consists in certain features of construction and combinations of parts hereinafter described, and pointed out in the claims.

In the accompanying drawings, Figure I is a side elevation, largely in section, of a machine or apparatus embodying my invention. Fig. II is a left-hand side elevation relative to Fig. I of the lower portion of the machine. Fig. III is a vertical section on line III-III, Fig. I, looking in the direction indicated by the arrow. Figs. IV, V, and VI are elevations, largely in section, of portions of the machine and illustrate the formation of the

product within the mold and the removal of the same upon the mold-bottom from the chamber of the mold.

Referring to the drawings, *a* designates a vertically-arranged open-ended case or section which forms the surrounding walls of the chamber of the mold. The section *a* is stationary, being secured in any approved manner to the stationary framework of the machine. The section *a* is open at its upper end to accommodate the introduction of the material required to be fed into the mold to make the brick or product which is to be formed by and within the mold and to accommodate the operation of a plunger *b*, employed to operate upon the material from above, and to accommodate also the passage of the mold-bottom *c* upwardly through and from the chamber of the mold. The section *a* is open at its lower end to receive the plunger *b*, which constitutes a support for the mold-bottom *c*, upon which the brick or product is formed within the mold. The plunger *b* is actuated in a vertical plane in any approved manner, and suitable mechanism for operating the said plunger is illustrated and hereinafter described.

In Figs. I and III a mold-bottom *c* is shown in position within the lower end of the chamber of the mold-section *a* and removably placed or resting upon the upper face or top of the plunger *b*, and the said chamber is shown supplied with material *g* upon and over the said bottom. The said chamber is uniform in dimensions from the upper end to the lower end of the mold, and the said bottom has the dimensions required to render it capable of snugly but easily fitting within the said chamber and to accommodate its removal when laden upwardly through and above the upper end of the mold-section *a*, so as to render the said laden bottom capable of being shoved from over the said section *a* onto a stationary table *d*, which is arranged in a horizontal plane and has its upper surface flush with the upper extremity of the mold-section *a*, and the laden mold-bottom is shoved or moved from the table *d* onto a pallet *e*, which is removably supported in any approved manner from the stationary framework of the machine and arranged with its

upper surface flush with the upper surface of the table *d*. The laden mold-bottom bearing the brick or product formed within the mold is removed from the mold onto the table *d* and thence onto the pallet *e* in any approved manner, and suitable mechanism for moving or actuating the said bottom onto the table *d* is illustrated and hereinafter described.

Fig. I shows several laden mold-bottoms *c* upon the table *d* and one upon the pallet *e*, and *k* designates the bricks or products upon the said bottoms.

One of the surrounding walls of the chamber of the mold-section *a* is provided a suitable distance below the upper end of the said section with a lateral slot *l*, which is just large enough in dimensions (see Figs. I and III) to accommodate the feeding of one mold-bottom *c* at a time and edgewise through the said slot onto the upper surface or top of the plunger *b*, which is lowered into its lowermost position preparatory to the introduction of the said bottom *c* into the position required to form the bottom of the chamber of the mold, which is formed by the mold-section *a* and the said mold-bottom *c* when the latter is applied. The said mold-bottom *c* is fed onto the lower plunger *b* in any approved manner, and mechanism suitable for feeding one mold-bottom at a time onto the said plunger is hereinafter described.

The unset plastic material is fed into the chamber of the mold from above in any approved manner, and pressure from above is exerted upon the material fed into the mold by an upper plunger *h*, which is applied and operated in any approved manner and has the dimensions required to render it capable of snugly but easily entering the chamber of the mold. Suitable mechanism for operating the plunger *h* is illustrated and hereinafter described. It will be observed, therefore, that the unset plastic material required to form the brick or product in the mold is fed into the mold and rests upon a mold-bottom *c*, which, as already indicated, is removably seated upon the lower plunger *b*, and the said material is compacted within the mold and upon the said bottom into the form of the brick or product which is to be made by the machine.

The operation of the machine or apparatus hereinbefore described is therefore as follows: The lower plunger *b* is brought into position ready to receive a mold-bottom *c*, which is then fed through the slot *l* onto the said plunger and into the position required to render it capable of ascending the chamber formed by and within the mold-section *a*, as shown in Figs. I and III. The material is then fed into the said chamber from above, whereupon the upper plunger *h*, which has been elevated out of the way preparatory to the feeding of the said material, is lowered into the said chamber, as shown in Fig. IV, and exerts pressure upon the material with-

in the said chamber, so as to form the brick or product for which the mold is designed. The material within the mold may be operated upon from below by the lower plunger as well as from above by the upper plunger, so as to compact the material from below as well as from above. The laden mold-bottom *c* is then elevated out of the mold-section *a*, as shown in Fig. V, by actuating the lower plunger upwardly to the extent required, and the said bottom upon being elevated far enough to bring its under surface next above the upper extremity of the said mold-section *a* is shoved or moved from over the said mold-section *a* onto the table *d*, as shown in Fig. VI, and thence onto the pallet *e*, and of course the upper plunger is elevated during the elevation of the said bottom *c* far enough to freely accommodate the removal of the elevated laden bottom onto the table. The pallet *e* as soon as it becomes laden with a row of laden mold-bottoms *c* is then removed and replaced by another and unladen pallet. Upon the removal of the laden mold-bottom *c* from the mold-section *a* onto the table *d* the lower plunger *b* is again lowered into its lowermost position, ready to receive another unladen mold-bottom. The mold-bottoms *c* have preferably a smooth upper surface.

It will be observed that by the machine or apparatus hereinbefore described a brick formed within the mold and composed of plastic material which has not set sufficiently to render the product capable of being directly handled without liability of mutilating or injuring the same is adequately supported upon the mold-bottom, especially when the brick is formed flatwise within the mold, as illustrated, and has the ordinary or conventional dimensions—a thickness of two inches, a width of four inches, and a length of eight inches—and rests, therefore, at one of its largest surfaces upon the said bottom, and it will be observed that only the mold-bottom upon which the brick rests is touched or handled during the period in which the setting of the material composing the brick takes place. The brick or product as soon as it has sufficiently set is removed from the mold-bottom interposed between it and the pallet *e* and stacked or stored away to harden, and the said mold-bottom is then returned to the machine for use again as a support for material formed into a brick or predetermined product within the mold in the formation of which the said bottom participates.

The upper plunger *h* is a vertically-reciprocating plunger engaging correspondingly-arranged slideways *m*, formed upon the stationary framework of the machine. The plunger *h* is operatively connected, by means of a pitman *n*, as shown in Fig. I, with the crank *o* of a suitably-driven crank-shaft *p*, which is arranged horizontally and suitably supported a suitable distance above the travel of the said plunger. The shaft *p* is opera-

tively provided with a driving-wheel r , to which power is applied in any approved manner.

The lower plunger b is a vertically-reciprocating plunger engaging correspondingly arranged slideways formed upon the stationary framework of the machine below the mold-section a . The plunger b is provided with a depending roller-bearing arm or stem t . The stem or arm t has two horizontal rollers u , as shown in Fig. III. The rollers u are arranged at opposite sides, respectively, of the said arm or stem and in line. The rollers u engage the cam-forming ways w , formed in corresponding cam-wheels x , which are operatively mounted upon a shaft y , arranged horizontally and a suitable distance below the travel of the plunger b . The shaft y is parallel with the upper shaft p and supported in any approved manner from the stationary framework.

A suitable operative connection between the shafts y and p (see Figs. I and III) comprises one or two sprocket-wheels 10, operatively mounted upon the shaft y and operatively connected, respectively, by a chain 12 with a sprocket-wheel 13, which is operatively mounted upon the upper shaft p .

The mold-bottom c is passed onto the lower plunger b through the slot l from a table 15, which has its upper surface flush with the bottom of the said slot. Next outside of the slot l and next over the table 15 is placed a pile of mold-bottoms c , and one bottom c is fed at a time from the said pile through the said slot onto the said plunger. Suitable means for feeding the lowermost bottom c of the pile of bottoms through the slot l comprises a horizontally-arranged slide 16, which rests upon and is movable longitudinally of the table 15, and the travel of the said slide extends to and flush with the adjacent side wall of the chamber of the mold. The slide 16 is normally arranged to engage the outer table-crossing edge of the lowermost bottom of the pile of bottoms c , and the said slide 16 engages slideways or guides 17, formed upon the table 15 at the side edges of the said slide, as shown in Figs. I and II. The thickness of the slide 16 does not exceed and is preferably somewhat less than the thickness of a mold-bottom c , so that there is no liability of the said slide engaging more than one bottom c at a time. The slide 16 is provided at its outer end with a roller 18, which extends into a slot 20, formed in and longitudinally of the upper arm of a vertically-tilting lever 22, which is fulcrumed, as at 21, to the stationary framework of the machine and has its lower arm extending into the path of a roller 23, with which one of the cam-wheels x is provided. A suitably-applied spring 24 acts to retain the lever 22 in its normal position, wherein the slide 16 is in its outer position, and the arrangement of the parts is such that the roller 23 shall during the rotation of

the shaft y come into engagement with the lower arm of the lever 22 and thereupon actuate the said lever against the action of the spring 24 in the direction required to cause the said slide to feed the lowermost bottom of the pile of bottoms c onto the said lower plunger. The spring 24 as soon as the lever 22 is released by the roller 23 during the said rotation of the said shaft returns the said slide into its outer and normal position.

The means for feeding the laden mold-bottom from the lower plunger b , when the said plunger is in its elevated position, onto the table is substantially the same as the means already described for feeding an unladen bottom onto the said plunger and comprises a horizontally-arranged slide 26, which rests upon and is movable longitudinally of a table 25, which is arranged above the table 15 and has its upper surface flush with the upper surface of the table 15, so that a laden mold-bottom upon the said plunger when the latter is elevated flush with the upper surfaces of the said tables d and 25 shall be in position to be engaged by the slide 26 at its edge which faces the said slide, and the said slide is thereupon actuated to remove the said bottom from the said plunger onto the table d . The tables d and 25 are arranged, therefore, at opposite sides, respectively, of the upper end of the mold-section a . The slide 26 engages slideways 27, formed upon the table 25 at the side edges of the said slide, as shown in Figs. I and II. The slide 26 is provided at its outer end with a roller or member 28, which extends into a slot 30, formed in and longitudinally of the upper arm of a vertically-tilting lever 32, which is fulcrumed, as at 31, to the stationary framework of the machine and has its lower arm extending into the path of a roller 33, with which one of the cam-wheels x is provided. A suitably-applied spring 34 acts to retain the lever 32 in its normal position when the slide 26 is in its normal position and does not overhang the chamber of the mold-section a , and the arrangement of the parts is such that the roller 33 shall during each rotation of the shaft y come into engagement with the lower arm of the lever 32 and thereupon actuate the said lever against the action of the spring 34 in the direction required to cause the slide 26 to engage the opposing edge of the elevated laden bottom and push the latter onto the table d , and the said spring as soon as the said lever is released by the said roller 33 during the said rotation of the said shaft promptly returns the said slide into its outer and normal position.

The means for feeding the plastic material into the chamber of the mold-section a from above comprises a suitably-applied hopper 35, having a discharge-spout 36, arranged to discharge at one side of the travel of the plunger b and above the slide 26 into the chamber of the mold. The hopper-spout 36 is provided internally with a vertically-arranged nor-

mally closed valve-forming slide 37, which is operatively connected at its upper end by a link 50 with a lever 38, which is fulcrumed at one end, as at 40, to the hopper 35, and a 5 suitably-applied spring 42 acts to retain the slide or valve 37 in its lower and normal or spout-closing position. The lever 38 is made in two sections pivotally secured together by a pin 43, which is arranged horizontally, and 10 the valve 37 is attached to the said lever by the said pin. The free end portion 44 of the lever 38 is therefore capable of tilting vertically independently of the remaining portion of the lever; but the said free end portion 15 44 to prevent it tilting upwardly independently of the remaining portion of the lever and to permit it to tilt only downwardly independently of the said remaining portion of the lever is provided with an arm or lug 20 45, which overhangs and normally rests upon the said remaining portion of the lever, as shown in Fig. I, and a suitably-applied spring 25 46 acts to retain the said lever-section 44 in its normal position. The plunger *h* is provided at its upper end with a laterally-projecting member 47, and the free end portion 30 44 of the lever 38 extends into the path of the said plunger member 47. The arrangement of the parts is such that the plunger *h* in its elevated position has its member 47 above the free end portion 44 of the lever 38, that the 35 said plunger member 47 during the downward movement of the plunger comes into engagement with the upper side of the free end portion 44 of the lever and tilts the said free end portion downwardly against the action of the spring 42 without acting upon the remainder of the lever, that the said plunger when it has been lowered into engagement 40 with the body of material in the mold-section *a* is far enough below the free end portion 44 of the lever 38, as shown in Fig. IV, to prevent the plunger member 47 during the next upward movement of the plunger from coming into engagement with the said lever until the laden mold-bottom has been elevated and fed onto the table *d*, whereupon the free end portion 44 of the lever will be engaged upon its under side by the said plunger member 47 during the said upward movement of the plunger, and the power applied by the plunger member 47 against the under side of the free end portion 44 of the lever 38 during the said upward movement of the plunger will result in tilting the said lever upwardly against the action of the spring 42 and, as required, to open the valve 37, so that another charge of material will pass to the chamber of the mold-section *a*. The hopper may 55 be provided internally with any device or mechanism (not shown) which will facilitate and accelerate the passage of material from the hopper to the mold, so that the feed of material to the mold will be sufficiently rapid 60 to supply the mold within the limited time with the proper amount of material, and obviously the valve 37 as soon as the free end

portion 44 of the lever 38 has been released by the plunger member 47 during the upward movement of the plunger *h* will be closed by the action of the spring 42.

The arrangement of the parts and the trend of the ways *w* of the cam-wheels *x* are such that during the operation of the machine the following operations occur: A mold-bottom *c* 75 is passed by the slide 16 onto the lower plunger *b* when the said plunger is in its lowermost position, that the proper amount of material is fed from the hopper 35 into the chamber of the mold over the said bottom during 80 the ascent of the upper plunger *h*, that the upper plunger descends upon the body of material thus fed into the said chamber and exerts pressure upon, and thereby compacts, the said material, that both plungers then ascend 85 and the laden mold-bottom is elevated above the table *d*, and the upper plunger releases the product upon the said bottom, and the slide 26 shoves the laden mold-bottom from the lower plunger onto the said table and returns promptly into its normal position upon 90 the performance of its function, and that the lower plunger, while the upper plunger continues to ascend, descends into its lowermost position and receives another unladen mold-bottom before another charge of material is fed from the hopper to the mold during the 95 said ascent of the upper plunger.

What I claim is—

1. In a machine for making products of the character indicated, a mold comprising a section which forms the surrounding walls of the chamber of the mold and having a bottom which is movable in a vertical plane and has such travel relative to the chamber-forming mold-section that the said bottom and the product formed within the said chamber and resting upon the said bottom shall be entirely removed from the said chamber, or the said chamber shall be closed by the said bottom 100 from below, according as the said bottom is in the one or the other of its extreme positions during its travel in a vertical plane, which chamber-forming mold-section is provided, at the bottom, with a lateral slot; a 105 plunger for effecting the actuation of and affording bearing to the said bottom; means for operating the plunger; means for feeding the mold-bottom through the aforesaid slot onto the plunger, and means for compacting 110 the material fed to the chamber of the mold.

2. In a machine for making products of the character indicated, a mold comprising a section which forms the surrounding walls of the chamber of the mold and having a bottom 115 which is movable upwardly through the said chamber, which stationary section is provided, at its lower end, with a lateral slot affording the passage of a mold-bottom therethrough; a plunger arranged to move in the said chamber and affording bearing to the bottom fed onto the plunger through the aforesaid slot; means for feeding the bottom onto the said 120 plunger through the said slot; means for op-

erating the plunger, and means for compacting the material fed to the chamber of the mold.

3. In a machine for making products of the character indicated, a mold comprising a section which is instrumental in forming the surrounding walls of the chamber of the mold, said mold having a bottom which is movable up and down and has such travel relative to the said chamber-forming section that the said bottom and the product formed within the said chamber and resting on the bottom shall be removed from the said chamber, or the said chamber shall be closed by the said bottom from below, according as the said bottom is actuated into the one or the other of its extreme positions; a vertically-movable support for the said bottom; means for compacting the material fed to the said chamber; means for actuating the said bottom-support; a removably-supported pallet arranged to receive the laden mold-bottom when the latter is removed from the aforesaid chamber, and means for feeding the laden bottom, when the latter is removed from the said chamber, onto the said pallet.

4. In a machine for making products of the character indicated, a mold comprising a section which forms the surrounding walls of the chamber of the mold and having a bottom which is movable in a vertical plane and has such travel relative to the chamber-forming mold-section that the said bottom and the product formed within the said chamber and resting upon the said bottom shall be entirely removed from the said chamber, or the said chamber shall be closed by the said bottom from below, according as the said bottom is actuated into the one or the other of its extreme positions during its travel in a vertical plane; a plunger arranged to afford bearing to the said bottom; means for compacting the material fed to the said chamber and comprising another plunger arranged to enter said chamber from above; a table arranged at one side of the mold in position to receive the laden bottom when the latter is freed from the chamber-forming mold-section; means for operating the lower plunger as required to bring the laden bottom in position to pass onto the aforesaid table; means for actuating the laden mold-bottom onto the said table, and a removable pallet arranged to receive the laden mold-bottom from the said table.

5. In a machine for making products of the character indicated, a mold comprising a section which forms the surrounding walls of the chamber of the mold and having a bottom which is movable upwardly through the said chamber; a plunger arranged to afford bearing to the said bottom and movable within the aforesaid chamber; means for compacting the material fed to the said chamber; means for operating the said plunger as required to elevate the laden mold-bottom above the chamber-forming mold-section; two ta-

bles arranged at opposite sides, respectively, of the upper end of the chamber-forming mold section; a feeding device on one of the said tables and arranged to engage and push the elevated laden bottom from the aforesaid plunger onto the other table; a shaft; means for operating the shaft; means for transmitting power from the shaft to the aforesaid plunger; a lever operatively connected with the said feeding device; means acting to retain the feeding device in its outer and normal position, and means arranged to operate the said lever and operatively connected with the aforesaid shaft.

6. In a machine for making products of the character indicated, a mold comprising a section which forms the surrounding walls of the chamber of the mold, said mold having a bottom which is movable upwardly through the said chamber; a plunger arranged to afford bearing to the said bottom and movable within the aforesaid chamber; means for compacting the material fed to the said chamber; means for operating the said plunger as required to elevate the laden mold-bottom above the chamber-forming mold-section; a removably-supported pallet arranged to receive the elevated laden mold-bottom, and means for feeding the said elevated bottom onto the said pallet.

7. In a machine for making products of the character indicated, a mold comprising a section which is instrumental in forming the surrounding walls of the chamber of the mold, said mold having a bottom which is movable up and down and has such travel relative to the said chamber-forming section that the said bottom and the product formed within the said chamber and resting on the bottom shall be removed from the said chamber, or the said chamber shall be closed by the said bottom from below, according as the said bottom is actuated into the one or the other of its extreme positions; a plunger arranged to afford bearing to the said bottom; means for compacting the material fed to the said chamber; means for operating the said plunger; a removably-supported pallet arranged to receive the laden mold-bottom, when the latter is removed from the aforesaid chamber, and means for feeding the laden bottom, when the latter is removed from the said chamber, onto the said pallet.

8. In a machine for making products of the character indicated, a mold comprising a section which forms the surrounding walls of the chamber of the mold and having a bottom which is movable upwardly through the said chamber; a plunger arranged to afford bearing to the said bottom and movable within the said chamber; means for compacting the material fed to the said chamber and comprising another plunger arranged to enter the said chamber from above; means for operating the upper plunger; means for feeding material to the chamber of the mold and comprising a hopper having a spout arranged to

discharge into the said chamber; a valve arranged to control the discharge from the hopper and normally closed; mechanism for operating the said valve to open the valve; 5 means acting to retain the valve in its normal position; means whereby the valve-operating mechanism is operated to open the valve during the upward stroke of the upper plunger; a table arranged at one side of the upper end of the chamber-forming mold-section; 10 means for operating the lower plunger as required to elevate the mold-bottom above the

chamber-forming mold-section and above the said table, and means for removing the elevated laden bottom from the lower plunger 15 onto the said table.

In testimony whereof I sign the foregoing specification, in the presence of two witnesses, this 12th day of April, 1902.

WILLIAM E. JAQUES.
